Lullabye Furniture Corporation, Stevens Point, Wis.,
a corporation of Wisconsin

Filed Aug. 10, 1960, Ser. No. 61,685

Term of patent 14 years

(Cl. D5—5)

FIG. 1 is a perspective view of a crib showing the design of my invention, and

FIG. 2 is an end view of a crib shown in FIG. 1.

The dominant features of my design reside in those portions shown in full lines in the drawings. The face of the headboard not shown is substantially the same in appearance as the side that is shown.

I claim:

The ornamental design for a crib, substantially as shown and described.
